GLASSWARE FORMING MACHINE

Clarence C. Kinker, Alton, Ill., assignor to Owens-Illinois Glass Company, a corporation of Ohio

Application April 19, 1934, Serial No. 721,326

8 Claims. (Cl. 49—42)

The present invention relates to improvements in glassware forming machines and more particularly to mechanism for raising and lowering the mold bottom plates which are associated with the usual finishing or blow molds.

An object of the invention is the provision of mechanism actuated by the opening and closing movements of the finishing mold halves to impart the desired movement to the mold bottom plate.

Another object is the provision in mechanism of the above character of yielding connection between it and the means for opening and closing the mold to thereby minimize the danger of breaking or distorting any of the various parts of the mechanism.

A further object is the provision of mechanism of the above character in which the mold bottom plate and holder therefor may be adjusted with ease to compensate for variations in the height of the finishing molds.

Other objects will be in part apparent and in part pointed out hereinafter.

In the drawings:

Fig. 1 is a fragmentary plan view of one form of machine in which the invention may well be embodied.

Fig. 2 is a fragmentary sectional view taken substantially along the line II—II of Fig. 1.

Fig. 3 is a detail sectional elevational view showing the finishing mold open and the corresponding bottom plate in its lowermost position.

Fig. 4 is a sectional elevational view taken substantially along the line IV—IV of Fig. 2.

Fig. 5 is a sectional elevational view taken substantially along the line V—V of Fig. 2.

Fig. 6 is a sectional view taken along the line VI—VI of Fig. 4.

Fig. 7 is a fragmentary front elevational view showing the finishing mold open and the corresponding bottom plate supported on a cam at the take-out position.

Fig. 8 is a detail sectional elevational view of the bottom plate holder and mechanism for raising and lowering it.

While the present invention is well adapted for embodiment in various types of bottle forming machines, it is for illustrative purposes shown herein in conjunction with the well known Lynch machine which is completely disclosed in Patent 1,788,312 dated January 6, 1931, and to which patent reference may be made for details of construction and operation omitted in the present application and in fact constituting no part of my invention.

Briefly, the illustrated machine consists of

blank and finishing mold tables 15 and 16 respectively, arranged side by side and rotated by mechanism 17 operating through a pinion 18 which runs in mesh with ring gears 19 on said mold tables. A blank mold unit 20 on the table 15 brings blanks or parisons periodically to a blank transferring station "T" between the tables. At this station the blanks are transferred to finishing molds 21 which are arranged in an annular series upon the finishing mold table 16.

Each finishing mold includes two sections 22 pivoted to a vertical hinge pin 23 and connected through links 24 to a slide block 25 which is mounted upon a pair of radially extending guide rods 26 and carries a cam roll 27. This cam roll 27, when the mold is standing at the blank transferring station, is adapted to be engaged by a mold closing device 28 (Figs. 1 and 2) which is common to all of the finishing molds and includes a horizontal piston motor 29 having a piston rod 30. At the outer end of this piston rod is a disk 31, which, when the motor is operated, engages the roll 27 on the slide block 25 causing said roll and slide block to move radially outward and close the mold about the blank "B" or parison.

Blowing mechanism "M" (Fig. 1) operates to expand the blanks or parisons during one of the periods of rest of the molds and a take-out device "D" of conventional or any preferred form, removes the finished articles at the article removing station "R" and places them upright upon a machine conveyor "C".

Associated with each finishing mold is a bottom plate 35 which may have a plunger 36 projecting upwardly therefrom or simply the conventional low crowned portion 37 on its upper face. This bottom plate is removably supported in the outer end of a pivoted arm 38 which is swung vertically into and out of operative relation to the mold at regular time intervals in synchronism with the opening and closing movements of the finishing mold sections 22. This mechanism which is actuated and directly controlled by operation of the slide block 25 may well embody the following construction. This arm 38 is separably and vertically adjustably mounted upon a rockable carrier 39 which in turn is pivoted to a horizontal hinge pin 40 extending through and journaled in a bearing block 41, the latter being attached to the finishing mold table 16. This arm 38 is formed with a pair of clamping fingers 42 which engage a dove-tail slideway 43 on the carrier 39 and are firmly engaged with the latter under pressure applied by a clamping bolt 44 connecting said fingers. A lever 45 may be attached as by

means of bolts 46 to one end of the rockable carrier 39 (Figs. 4 and 6) and extends radially inward through an opening 47 in the finishing mold table 16 and at its inner end is pivoted to a yielding connector 48 through which motion is imparted to said lever from the mold closing and opening mechanism.

This yielding connector includes a collar 49 connected to the lever 45 by means of a hinge pin 50. Arranged within this collar 49 is a sleeve 51 of slightly greater length than the collar and within this sleeve is a rod 52 which is fixed against movement relative to the latter. The opposite ends of this rod 52 are secured in a pair of externally threaded sleeves 53, one of which is connected by means of a horizontal hinge pin 54 to the slide block 25 of the mold opening and closing mechanism. A coil spring 55 encircles the rod 52 and upper sleeve 53 above the collar 49 and is confined between a washer 56 and spring tension adjusting nut 57. Below said collar 49 a coil spring 58 encircles said rod and the lower sleeve 53, this spring being confined between a washer 59 and a spring tension adjusting nut 60. An adjustable set screw 61 carried by the lever 45 is positioned to engage a part 62 of the finishing mold table to thereby limit upward swinging movement of the bottom plate supporting arm 38 to insure proper positioning of the bottom plate 30 preparatory to the final closing of the corresponding finishing mold.

In order to support the bottom plates against downward movement when the finishing molds open and prior to removal of bottles therefrom, a stationary track 63 (Figs. 1, 2, and 8) is arranged at the article removing station "R". This track includes a horizontal top surface 64 upon which the bottom plate rides as it approaches the article removing station and rests momentarily thereon at said station. A downwardly inclined top surface 65 at one end of this track allows the bottom plates to move downwardly after the finished articles have been removed from the finishing molds and the latter moved away from the article discharging position.

In operation, blanks or parisons are brought in succession to the blank transferring station "T" and suspended by the blank forming unit 29 in position to be enclosed by the finishing molds. Assuming that a blank is so positioned and a finishing mold is standing at the blank transferring station, the next operation involves actuation of the mold closing motor 28. This results in outward movement of the slide block 25 which operates through the links 24 to bring the finishing mold sections 22 together. Simultaneously with such outward movement of the slide block the connector 48 is moved to rock the lever 45 and thereby impart upward movement to the bottom plate supporting arm 38. Shortly after the slide block begins its forward movement the upper coil spring 55 is compressed to a degree bringing the corresponding washer 56 into engagement with the collar 49. At the time the rod 52 assumes a vertical position parallel or substantially parallel with the axis of the corresponding finishing mold, the bottom plate 35 will have reached its uppermost position. Any over-travel of the connector beyond this vertical position to permit additional outward movement of the slide block in closing the mold, is permissible due to the presence of the coil spring 55 which functions as a safety feature preventing breaking or excessive straining of any of the elements between the slide block 25 and hinge pin 40. Upon arriv-

ing at a point slightly in advance of the article removing station the finishing mold is opened by engagement of the cam roll 27 with a stationary cam 66. Ordinarily such operation would be accompanied by lowering of the bottom plate and premature discharge of the finished article. However, due to the presence of the track 63, the bottom plates are supported in a horizontal plane during such opening of the finishing mold and while it stands at the article removing station during operation of the take-out device "D". Although the bottom plate remains in position to support the finished article during and following the opening of the finishing mold, the connector 48 is returned to its original position due to the inward travel of the slide block 25 involved in opening the finishing mold. Because the lever 45 cannot swing about the hinge pin 40 independently of movement of the bottom plate supporting arm 38, such return of the connector to its original position causes upward sliding movement of the rod 52 in the collar 49 and compression of the lower coil spring 58. Consequently, when the mold table is indexed to move the finishing mold away from the article removing station this lower coil spring 58 expands and insures lowering of the bottom plate and travel thereof along the downwardly inclined surface 65 of the track 63. Thus, the plate is positioned in a plane below that occupied by the bottom end of the blanks at the transferring station.

Modifications may be resorted to within the spirit and scope of the appended claims.

What I claim is:

1. In combination, a partible finishing mold, a bottom plate movable into and out of cooperative relation to the mold, mechanism for opening and closing the mold, an arm supporting the plate, a lever rigidly attached to the arm, a connector between said arm and mechanism whereby operation of the latter rocks the lever and through it imparts vertical movement to the bottom plate, said connector comprising a collar pivoted to the free end of the lever, a rod slidably arranged in the collar and extending beyond the opposite ends thereof, coil springs encircling the rod at opposite sides of the collar, and means for retaining said springs on the rod.

2. In combination, a partible finishing mold, a bottom plate movable into and out of cooperative relation to the mold, mechanism for opening and closing the mold, an arm supporting the plate, a lever rigidly attached to the arm, a connector between said arm and mechanism whereby operation of the latter rocks the lever and through it imparts vertical movement to the bottom plate, said connector comprising a collar pivoted to the free end of the lever, a rod slidably arranged in the collar and extending beyond the opposite ends thereof, coil springs encircling the rod at opposite sides of the collar, means confining the springs to predetermined areas of the rod, means for temporarily supporting the bottom plate against downward movement during opening of the mold to thereby compress one of said springs, and means for releasing the bottom plate whereby it is lowered under pressure created by expansion of said spring.

3. In combination, a partible finishing mold, mechanism including a horizontally movable slide block for opening and closing the mold, a bottom plate adapted to close the lower end of the mold, a rockable carrier for the bottom plate, a lever attached to said carrier, a collar pivoted to the free end of the lever, a rod slidably extending

through said collar, means pivotally connecting the upper end of the rod and said slide block, coil springs encircling the rod above and below said collar, and means whereby the coil spring below the collar is placed under tension during opening of the mold and thereafter is released to effect positive downward movement of the bottom plate.

4. In combination, a partible finishing mold, mechanism including a horizontally movable slide block for opening and closing the mold, a bottom plate adapted to close the lower end of the mold, a rockable carrier for the bottom plate, a lever attached to said carrier, a collar pivoted to the free end of the lever, a rod slidingly extending through said collar, means pivotally connecting the upper end of the rod and said slide block, coil springs encircling the rod above and below said collar, means interposed between the collar and adjacent ends of the springs for definitely spacing the adjacent ends of the coil springs from each other and at times from said collar, and a spring tension adjusting nut engaging the outer end of each spring.

5. In combination, a partible finishing mold, mechanism including a horizontally movable slide block for opening and closing the mold, a bottom plate adapted to close the lower end of the mold, a rockable carrier for the bottom plate, a lever attached to said carrier, a collar pivoted to the free end of the lever, a rod slidingly extending through said collar, means pivotally connecting the upper end of the rod and said slide block, coil springs encircling the rod above and below said collar, spacing means interposed between the collar and adjacent ends of the coil springs, a spring tension adjusting nut engaging the outer end of each spring, and means for supporting the bottom plate against downward movement during opening of the mold and thereby placing the lower spring under compression and thereafter releasing said spring to effect positive downward movement of the bottom plate.

6. In combination, a partible finishing mold comprising a pair of sections, a vertical hinge pin upon which said sections are pivoted, a slide block, links connecting the slide block and mold

sections, means for moving the slide block to thereby open and close the mold, a bottom plate adapted to close the lower end of the mold, an arm on which the bottom plate is supported, a rockable carrier for said arm, a lever attached to the carrier, a collar pivoted to the free end of said arm, a rod slidingly extending through said collar and connected at one end to the slide block, a coil spring encircling the rod between said collar and the slide block, and a coil spring encircling the rod below said collar.

7. In combination, a partible finishing mold comprising a pair of sections, a vertical hinge pin upon which said sections are pivoted, a slide block, links connecting the slide block and mold sections, means for moving the slide block to thereby open and close the mold, a bottom plate adapted to close the lower end of the mold, an arm on which the bottom plate is supported, a rockable carrier for said arm, a lever attached to the carrier, a collar pivoted to the free end of said arm, a rod slidingly extending through said collar and connected at one end to the slide block, a coil spring encircling the rod between said collar and the slide block, a coil spring encircling the rod below said collar, and means for holding the carrier and lever against movement during opening of the mold to thereby compress the lower coil spring and thereafter releasing said carrier and lever for rocking movement due to expansion of said lower coil spring.

8. In combination, a partible finishing mold, a bottom plate movable vertically into position to close the lower end of the mold, mechanism for opening and closing the mold, means comprising a spring device actuated by operation of said mechanism for imparting movement to the bottom plate, said spring device including a pair of coil springs, means for placing the springs under tension one at a time whereby one spring while under tension operates to positively move the bottom plate away from the mold and the other spring while under tension assists in moving the bottom plate into cooperative position relative to the mold.

CLARENCE C. KINKER.
